UNITED STATES PATENT OFFICE

JAROSLAV BENDA, OF PRAGUE, CZECHOSLOVAKIA

FOOTWEAR

Original application filed October 11, 1924, Serial No. 743,140, and in Czechoslovakia October 9, 1923.
 Divided and this application filed May 11, 1926. Serial No. 108,402.

This invention is a division from application Serial No. 743,140 filed October 11, 1924.

In ordinary welted footwear, a great deal of labour is spent on the after-treatment of the welt. Special machines are required for this after-treatment which, particularly the waxing and burnishing must be executed by skillful hands in order to prevent the upper from being damaged in the process.

10 The object of the present invention is to obviate this labour, and the invention consists in the provision of a welt of patent leather.

Since the ordinary patent leather is too soft and porous to form by itself a substantial welt, the latter is according to the invention made up of two strips, a main strip of canvas or ordinary leather and a facing strip of patent leather. The main strip is 20 stitched to the sole, while the facing strip is cemented down by means of an acid, water and sweat proof cement, for instance a celluloid solution.

Fig. 1 of the accompanying drawings represents a sectional view of a McKay boot to 25 which the invention is applied,

Fig. 2, a plan of the sole with attached welt,

Fig. 3, a sectional view of a boot having 30 a compound welt, and

Fig. 4, a side view of the unfinished boot.

In the McKay boot shown in Fig. 1, a welt 3 of patent leather is cemented to the sole 1 around the upper 2 by means of an acid, water 35 and sweat proof cement, for instance a solution of celluloid or other cellulose derivative. The lacquered surface 4 of the welt obviates after-treatment of the latter and saves labour and machinery. The welt is preferably applied to the sole 1 as shown in Fig. 2 when the sole is prepared.

Figs. 3 and 4 show a welt 3 composed of two strips 5 and 6 the lower one of which is 40 made of canvas or ordinary leather and connected by double stitches 7 to the sole 1. The upper strip is made of patent leather and is subsequently cemented down by means of a celluloid cement so as to cover the surface 8 and the stitches 7.

50 In the case of pasted footwear, the welt

is stitched to the upper with the flesh side outermost. This obviates the usual roughing of the grain side of the upper to receive the welt. The welt is cemented by means of a celluloid solution to the sole and finished off 55 flush with the latter.

I claim:

1. A welted footwear wherein the welt is composed of a body strip and a facing strip 60 made of different materials, the body strip being stitched to the sole and the facing strip cemented to the body strip by means of a celluloid solution.

2. A welted footwear according to claim 1 wherein the body strip is composed of canvas and the facing strip of patent leather. 65

In testimony whereof I have signed my name to this specification.

JAROSLAV BENDA.
